UNITED STATES PATENT OFFICE.

HENRY E. COY, OF MANSFIELD, OHIO.

MACHINE FOR THREADING THE POINTS OF LAG-SCREWS.

SPECIFICATION forming part of Letters Patent No. 276,671, dated May 1, 1883.

Application filed October 13, 1882. (No model.)

To all whom it may concern:

Be it known that I, HENRY E. COY, a citizen of the United States, residing at Mansfield, in the county of Richland and State of Ohio, have invented certain new and useful Improvements in Machines for Threading the Points of Lag-Screws; and I do hereby declare the following to be a full, clear, and exact description of the invention, such as will enable others skilled in the art to which it appertains to make and use the same.

The invention relates to an improvement in machines for cutting threads on the points of lag bolts or screws. In the process of manufacturing lag-bolts the shank of the same is of uniform diameter, and is provided with the usual spiral thread, the point of the bolt being left blank.

The object of the present invention is to thread this point so that it may be made to enter wood or other material without first preparing a hole to receive it; and it (the invention) consists of the elements hereinafter described, and particularly pointed out in the claims.

The exact nature and advantages of the invention will be readily understood from the detailed description hereinafter presented, reference being had to the accompanying drawings, in which—

Figure 1 is a top view of a machine embodying the elements of the invention. Fig. 2 is a side view of the same. Fig. 3 is an end view of the clamping-heads and operating-lever, made on the line $y-y$ of Fig. 1, looking in the direction of the arrow; and Fig. 4 is an end view of the head carrying the tools for cutting the thread, made on the line $x-x$, and looking in the direction of the arrow. Fig. 5 is a vertical transverse section through the small wheels $t-t$ and the blocks Q .

In the drawings, A denotes the head which imparts the revolving motion to the screw to be cut. This head consists of two standards, $a-a$, in which is journaled the shaft B , having the usual feather upon its surface, which enters a groove formed in the cone-shaped clutch b , and supplied upon its front end with the screw-holder C , as indicated in the drawings.

D indicates the belt-wheel, which is placed loosely upon the shaft B and in juxtaposition to the cone-shaped clutch b , which latter is operated to enter or recede from the belt-wheel

D by means of the lever d . Thus, when I desire the machine to remain at rest without stopping the power, I throw the clutch b away from contact with the belt-wheel D ; and when it is desired to start the machine again the clutch b is made to enter the wheel D , under which conditions the motion will be communicated to the shaft B and its connections.

The screw to be treated has its head inserted in the screw-holder C , the body of the screw projecting forward on a horizontal plane. The screw-holder will be a metallic piece fitted on the shaft B , and having a head or pocket adapted to receive the head of the screw.

Upon the base E , which supports the head A , is also placed the head F , which is arranged in advance of the head A , and carries the screw-clamping parts and the tools for threading the point on the screw, together with mechanism which will be described hereinafter. The head F consists of a base, G , adjustably secured to the base E by the screw d' , having a head upon each end, the head on the lower end fitting in the groove e , and the head of the upper end penetrating the lower part, f , of the base G . The base G f may be secured in any set position upon the base E by the bolt d' , and is provided upon opposite sides with the standards H , upon the upper ends of which are pivotally secured the cam-levers I , one being on the upper end of each standard.

Upon the upper ends of the standards also are pivotally secured the arms h , which are pulled by springs toward the outer ends of the cam-levers I , the purpose of which will be explained more fully in the following description. The edges of the part f of base G are cut to form guides for the auxiliary base J , which slides thereon.

Upon the outer end of the base J is formed the transverse guide K , upon which the two standards L have a transverse sliding movement toward or from each other, according as they are acted upon by the cams m cut in the plate M , which is operated by the lever N .

Upon each of the standards L is a pin, n , which enters the cams m , and communicates the movement influenced by the cams to the standards L .

In the upper portion of the standards L , preferably at their upper inner corners, are secured the sections O , forming the screw-clamp. This clamp is made in two sections and mounted

upon the movable standards L, so that they may be separated, the screw inserted, and then closed upon the same. The interior of the screw-clamp O will be provided with a few male thread corresponding with the thread upon the screw the point of which is to be threaded, so that as motion is imparted to the machine and is communicated to the screw it will feed the sliding base J, carrying the point-threading tools, by meshing with the thread in the screw-clamp.

The standards L are recessed at P, as indicated, in which recesses are placed the transversely-sliding blocks Q, upon which are secured by set-screws or other suitable means the point-threading tools R. The blocks Q have a tendency to fly outward from each other when they have been moved toward each other during the operation of the machine. One of the blocks Q is shorter than the other block, whereby one of the point-threading tools is lower than the other. One of the point-threading tools is placed with its longer point downward and the other with its longer point uppermost, whereby when the two points are brought against the screw to be treated they will make the proper incision.

Upon the outer sides of the sliding blocks Q are secured, between suitable lugs or ears, the small friction-wheels t, which, as the sliding base J, carrying the screw-clamp O and point-threading tools, is moved on the part f of base G, will bear against the inclined surfaces of the pivotally-secured cam-levers I. The front ends of the levers I project inward beyond their rear ends, so that when the base J, carrying the point-threading tools, is moved forward the wheels t will be pressed inward by the projecting surfaces of the levers I, and in turn will cause the blocks Q, carrying the point-threading tools, to advance toward each other, bringing the tools nearer each other, so as to thread the end of the screw being manipulated. After the wheels t have reached the forward ends of the levers I, the blocks Q will strike the ends of the arms h, forcing them outward, and permitting the levers I to turn on their pivots. The projecting surfaces are thus made to recede from the wheels t, at which time the springs S will cause the blocks Q to spring outward from each other and free the point-threading tools R from contact with the screw. Upon the return of the base J, carrying the screw-clamp and point-threading tools, toward the head A, the arms h and levers I will assume their former position, the arms h being controlled by their springs, and the levers I being actuated by the wheels t striking their rear ends, the effect being to throw the projecting surfaces at the front ends of the levers inward, as before.

Around the edge of the base E is formed a groove or trough, in which the liquid that the operator employs upon the screws being treated is placed.

The operation of the invention is as follows:

The screw being inserted in the head C, as indicated, the standards L are separated by the movement of the lever N and cams m, and moved so that the screw will be between the two sections of the screw-clamp O, when the lever is depressed and the standards L brought toward each other, which has the effect of closing the clamp upon the screw, the point-threading tools R being adjusted according to the size of the screw and the depth to be cut. Motion is then imparted to the shaft B by a suitable belt acting upon the band-wheel D. The revolving movement of the screw, acting upon the threads of the screw-clamp, forces the slide J, carrying the said clamp and the cutting-tools, forward between the standards H, whereby the tools are caused to approach each other and thread the end of the screw, the movement of the point-threading tools being regulated, in the manner above described, by the levers I and arms h. After the tools R have completed their incision they will spring outward, as aforesaid, and permit the screw to be withdrawn.

What I claim as my invention, and desire to secure by Letters Patent, is—

1. In a machine for threading the points of lag-screws, the clamping-jaws O, having a female thread and mounted upon the sliding standards L, provided with the cam-plate M, and lever N, in combination with the sliding blocks Q, carrying the point-threading tools R, substantially as set forth.

2. In a machine for threading the points of lag-screws, the blocks Q Q, having upon their outer edges the wheels t t, and carrying the point-threading tools R R, in combination with the sliding standards L L, springs S S, and pivoted former-levers I I, substantially as described.

3. In a machine for threading the points of lag-screws, the base G f, adjustable on the bed E, and the sliding base J, carrying the threaded clamping-jaws O O, in combination with cam-plate M, lever N, blocks Q Q, carrying point-threading tools R R, springs S S, and former-levers I I, substantially as specified.

4. In a machine for threading the points of lag-screws, the longitudinally-sliding base G f, guide K, carrying the blocks L L, and threaded screw-clamp O, in combination with blocks Q Q, carrying the point-threading tools, and having transverse movements toward and from each other, substantially as specified.

5. In a screw-threading machine, the combination of the sliding base J, the transversely-sliding standards L, the screw-clamp O, the sliding blocks Q, and the point-threading tools R, the clamp and tools being capable of independent movements, substantially as set forth.

In testimony whereof I affix my signature in presence of two witnesses.

HENRY E. COY.
